GARMENT BUTTONING POST

Emil Suhajda, Chicago, Ill., assignor to G. H.
Bishop Company, Chicago, Ill., a corporation of
Illinois

Application December 22, 1945, Serial No. 636,686

8 Claims. (Cl. 223—85)

1

This invention relates to a garment buttoning post for use in laundries particularly, where convenience and expedition of properly buttoning and inspecting garments, such as shirts, for instance, is an important consideration in the handling of the product.

In the usual laundry, the buttoning takes place between the ironing and folding steps, the garments being placed in piles after ironing and then before being taken to the folder an operator sees to buttoning the same. This is usually done without removal of the garment from the pile and, owing to the inconvenience of accomplishing same under the conditions, only the collar button and one or two others down the front of the garment may be buttoned and any inspection of the garment is apt to be more or less perfunctory.

It is an object of this invention to provide a garment buttoning post so that the garment may be taken from the pile and applied thereto in a simple, convenient and expeditious manner, so that the garment may be suspended therefrom for buttoning at ease and all buttons, if desired, be buttoned, so that the garment may be readily revolved for complete inspection and so that when through buttoning and inspection the garment may be freed from its support without any substantial effort, without mechanical manipulations of the support and without any disturbance or damage to the upper collar button or to the collar or shirt or garment otherwise, the post automatically, instantly and without attention of the operator placing itself in condition to receive the next garment. The garment is then ready for the folder or folding step.

In carrying out the invention and the various objects thereof, a supporting post in the form of a portable standard which may have a side T-bracket attached for the temporary support of garments to be buttoned, a wall bracket, extension rod from ceiling or otherwise and preferably forming an overhead rigid support for the hanger is provided with a hanger which may be collapsible and vertically swiveled on the support and adjustably disposed at a convenient height for the worker and the work in hand. The garment may be readily placed on the hanger in convenient position for buttoning at ease, rotating the same for inspection, and pulling the garment down off the hanger without any appreciable effort and without the necessity on the part of the operator of going through any mechanical manipulations of the device.

Further carrying out the invention and its ob-

2

jects, the hanger is provided with a central body portion, which may be termed a neck block, and opposed side arms projecting therefrom on which the shoulder sections of the garment may rest in the process of buttoning and inspection. These side arms of the hanger are made collapsible when it is desired to remove the garment from the hanger, and preferably without the necessity on the part of the operator of mechanically manipulating the same or even touching it.

A further feature and object is that the garment may be removed from the hanger by a simple slight pull thereon requiring no appreciable effort on the part of the operator and without mussing or rumpling of the garment or damage to the collar, collar button or otherwise.

Still further features and objects are that the side arms, which, while sufficiently strong in their normal position to sustain the garment suitably for buttoning and revolving for inspection, may be readily collapsed downwardly to free the garment by a slight pull thereon and then instantly restore themselves to normal position for the reception of another garment for like buttoning and inspection.

A still further feature and object is the provision of side arms connected to the neck block of the hanger so as to be rotatable with respect thereto in a downward direction from the normal garment-suspending position to free the garment therefrom when desired.

Further features, objects and advantages severally are the provision of a hanger for the step described, in which the side arms are collapsible downwardly by a slight pull on the garment and are spring-returned to normal sustaining position when freed from the garment; in which smooth stiff arms are spring-held in normal outward garment-suspending position, are readily collapsed downwardly by a slight pull on the garment, and are spring-returned to normal position when freed of the garment; in which stiff garment-sustaining arms are connected to the neck block in whole or in part by coiled springs tensioned to hold the arms in outstretched garment-suspending position to sustain the garment while buttoning and revolving for inspection, enabling the garment to be freed therefrom by a slight downward pull thereon and serving to return the arms to raised normal position when so freed of the garment; in which, in one form, a swiveled neck block is provided with a coiled spring extending across the same, with side arms attached to the ends of the spring and tensioned to hold

the arms outwardly in garment-sustaining position to hold the garment for buttoning and inspection and collapsible to free the garment by a slight downward pull thereon and then to raise the arms to normal position when freed of the garment, and in which, in another form, the arms are pivoted or hinged to a preferably hollow neck block and are spring retained in their outward garment suspending positions by springs preferably within the block so that the garment may be freed from the arms by a slight pull thereon, the springs serving to return the arms to normal position when freed of the garment.

Further objects and advantages will appear from the detailed description and claims to follow, in connection with the accompanying drawing, which illustrates, by way of example and not of limitation, two embodiments of the invention, and in which—

Fig. 1 is an elevation of a garment buttoning post of the portable floor type and indicating in dotted lines a garment suspended from the hanger of the post, the hanger being of the collapsible form shown in detail in other figures of the drawing;

Fig. 2 is a side view of the said hanger on a larger scale, parts being shown in section;

Fig. 3 shows the post in the form of a ceiling rod extension supporting the hanger at its lower end, or, as shown in dotted lines, a side wall bracket may be used;

Fig. 4 is a bottom plan view of the hanger;

Fig. 5 is a central cross-section through the neck block of the hanger, substantially on the line 5—5 of Fig. 2;

Fig. 6 is a side elevation of another form of the hanger, the neck block in the form of a hollow inverted cup being shown in section;

Fig. 7 is a bottom plan view of the same; and

Figs. 8 and 9 are, respectively, side and bottom plan views of an improved swivel.

In these drawings, and referring first to Figs. 1 to 5, the garment buttoning post in Fig. 1 is shown in the form of a portable standard 10, preferably of suitable telescoping pipe, as indicated at 11, to vary the height of the post to accommodate the worker or for other reasons, a relatively heavy base 12, as of metal, being provided to rest on the floor and serving to sustain the post in upright stationary position as against all normal, lateral and other stresses apt to be imposed thereon during use and regardless of whether it is in vertical alignment with the garment above or not.

The upper end of the standard is curved over, as at 13, to support the hanger, generally designated by numeral 14, from overhead.

This support of the hanger from the top or overhead facilitates the ready removal of the garment, which is buttoned together on the hanger and removed therefrom in a downward direction. A support of the hanger from below would obviously interfere with such removal.

The supporting post in its overhanging or overhead supporting function of the hanger may take the form of a ceiling rod or pipe 15 as shown in Fig. 3, suitably attached to the ceiling of the room and preferably also extensible by telescoping sections, as indicated at 16, or otherwise, suitably to adjust the height of the hanger 14 from the floor. Or it may take the form of a side wall bracket to be suitably attached to a vertical wall or surface of the room, as indicated in dotted lines at 17 in said Fig. 3, this also being preferably adjustable by telescopic sections as indicated at

18, or otherwise, properly to locate the hanger 14 for most convenient use by the operator and in the room.

The hanger 14 includes a neck block 19, in this instance of wood or any suitable material, which may be bell-shaped in side view as seen in Fig. 2, that is, narrower at the top portion 20, sloping edges 21 and flaring at the bottom as at 22 and with a substantially vertical lower edge rim portion 23. This block 19 may be of substantial thickness as shown in Fig. 5, with flat vertical sides or faces as shown, and all corners are preferably rounded off substantially as shown except at the bottom. The neck of the garment, collar, collar band and associated material engage this neck-block and contact therewith more or less in the application of the garment thereto and in the manipulation and removal thereof, and accordingly, the exterior surface of the block is made smooth and without sharp corners or projections to avoid any damage to the material and to facilitate suitably placing the garment thereon, manipulating it while buttoning or otherwise, and eventually in slipping the garment off the block and removing it, as hereinafter described.

This block may be of any desired color, of course, but it has been found that black is satisfactory for laundry purposes, harmonizes with the hanger arms to be described later, and, if the block be made of wood, the same may be readily stained, painted or enameled to provide an extremely smooth surface.

The standard 10 may have a side bracket 24 suitably attached thereto, preferably having a T head, as indicated, on which one or more ironed garments may be hung temporarily awaiting removal to the hanger for buttoning. In case of the suspension of the hanger from the wall or ceiling, such bracket and head 24 may be on an individual portable stand or other support.

The neck-block 19 is suspended from the supporting post above preferably by a swivel connection to facilitate the placing of the garment thereon, facing it to the operator or turning it to the most convenient angle or position for buttoning and to enable the garment after buttoning or at other times to be revolved or swung about on a vertical axis for all-around inspection of the garment.

This swiveling connection may be readily accomplished in the present instance by a coupling sleeve 25 threading on the lower end 26 of the overhead post support, whether of the portable, ceiling or side-wall type, and having its inturned flange 27 rotatably engaging under the socketed circular head 28 of captive screw or bolt 29 secured to and projecting upwardly from the top of the neck block 19. If desired, the sleeve 25 may be a straight section, threaded internally throughout its length, and the flange 27 replaced by a threaded washer screwed into the lower end of the sleeve and revolvably supporting the head 28 of the bolt 29.

The bolt 29 may be readily secured to the neck block 19 by inserting it through an aperture in the top of the block which intersects a larger-diameter aperture 30 from the side, as shown in Figs. 2 and 5, in the dead end of which a nut 31 has been placed, and threading the end of the bolt 29 into this nut 31. The nut 32 on the bolt at the top of the block may then be tightened to draw up and embed the corners of the nut 31 in the material of the block and thus secure the bolt 29 firmly in the neck block.

The head 28 of the bolt 29 is suitably socketed

to receive a wrench or tool to enable the bolt to be turned into or out of the nut 31. In assembling, the sleeve 25 is first placed on the bolt 29 and then the nut 32. The bolt 29 is then secured to the block 19, as related, and the sleeve 25 threaded onto the overhead support 26.

By this means, the neck-block is secured and swiveled to the overhead post support and may be readily turned and swung about the vertical axis as desired.

The hanger is provided with opposed side arms 35 on which the shoulder sections of the garment may rest during the process of buttoning and inspection, as indicated in Fig. 1, where a garment 36, such as a shirt, in dotted outline, is intended to be shown suspended or hung on the post and hanger.

Since the garment when buttoned and inspected must be removed from the hanger without rumpling, disturbance of the collar or damage to the collar button or otherwise, provision is made for the ready withdrawal of the arms from their normal garment-suspension position whereby the garment may be easily and quickly removed from the hanger, undisturbed in appearance and condition. This is preferably accomplished by making the hanger collapsible, so that the garment may be readily removed therefrom. Thus the side arms 35 may be made to collapse downwardly to free the garment, and the arrangement preferably is such that the withdrawal of the arms from their supporting positions is caused by a slight downward pull on the garment, and this preferably without other mechanical manipulation of the hanger. In the form shown, the side arms 35 are caused to rotate or pivot downwardly from the neck-block 19, as indicated in dotted lines in Figs. 1 and 2, to free the buttoned garment from the hanger, and this may be done by a slight pull, without substantial effort, on the garment itself.

After the buttoned garment is removed from the hanger, the side arms may be restored to normal garment-supporting position. This likewise is preferably automatic so that no hand or mechanical manipulation of the hanger may be necessary to restore the arms. For the latter purpose the side arms 35 are preferably connected with the neck-block 19 by spring-controlled connections which automatically return the arms to normal when the garment is removed therefrom. These spring-controlled connections may also retain the arms in their normal garment-suspending position as against the weight of the garment and any downward stresses thereon occurring from the buttoning and inspection operations.

In the particular embodiment shown in Figs. 1 to 5, the arms 35 are preferably circular in cross-section, slightly tapering and enlarged toward their outer ends, and the inner end of each is secured to the projecting end 37 of a coiled spring suitably secured in the lower edge part of the neck-block 19. This spring end 37 may be secured to the arm in any desired way. As shown, a short metal stem 38 is threaded into the end of the arm and the end 37 of the coil spring is threaded over the projecting end of the stem and secured thereto, as by soldering, brazing, welding, or the like. The arm may be of any suitable material. Wood or molded material may be used and the stem 38 or the end 37 of the coil spring, or both may be molded in the material of the arm when formed. The exterior of the arm is finished with a smooth surface to

permit the garment to be readily applied thereto, manipulated and adjusted thereon, and pulled off the same without harm to the material or a tendency to adhere thereto.

The projecting coiled-spring ends 37 which carry the side arms 35 preferably form the ends of a single coiled spring 40, which may be located in a suitable groove in the bottom of the neck-block 19, as shown, and which may be secured firmly and held therein by a thin plate 41 overlying the same and secured in place by screws 42. This plate 41 engages the spring and holds it in place as indicated.

The plate 41 terminates short of the edge of the neck-block 19 to allow the ends of the coiled spring to curve downwardly to permit the side arms 35 of the hanger to collapse downwardly sufficiently to enable the garment to be readily drawn downwardly and off the arms. This coiled spring, which may be of spring steel or any suitable spring material, is tensioned to hold the arms 35 outwardly in garment-holding position and to hold the garment while being buttoned and turned about for inspection as shown and described, but the ends yield to a slight downward pull on the garment which is given without substantial effort on the part of the operator to permit the arms 35 to collapse downwardly, as indicated, into garment-freeing position. After the garment is so drawn off the arms, the springs cause them automatically to snap back into garment-holding position ready to receive another garment for buttoning.

In such operation of the hanger, no special mechanical manipulation of the hanger is required on the part of the operator, who pays no attention thereto other than to hang the garment thereon, properly button it, revolve it for inspection, and then draw it off from the hanger by a slight pull thereon without special effort, and without disturbance of the collar, mousing of the garment or damage to the collar button. The coiled-spring connections provide gentle curves at the bends of the spring ends which are smooth-surfaced, present no corners or projections to catch in the fabric of the garments, and are practically noiseless in operation even in snapping back to normal positions, since there are no rigid abutments for the arms to strike against. The bends in the coiled springs are large enough to prevent undue stress or separation of the coils at any particular point thereof, the bending effects being distributed among the various coils of the bends, which makes for long life of the springs.

In the form of the invention shown in Figs. 6 and 7, the same type of rigid overhead support and swiveled connection 25 of the hanger therewith as in the first form may be provided. The hanger arms 50, however, are rotatively mounted on pivots or axes at their inner ends near the bottom of the head block 51 so as to swing down into garment-freeing positions and are spring-raised and maintained outwardly. The spring means for this purpose may take the form of coiled springs 52 located within the outer confines of the head block 51 and secured at their lower ends by loops 53 and eyelets 54 with the arms 50, the eyelet ends passing through suitable apertures in the arms and reversely bent at the ends as indicated in Fig. 7 or by other suitable means. The upper ends of the springs 52 may be secured in the head block 51 as by integral loops 55 around the bolt 56, corresponding to bolt 29 in the first form, and tightened and held in place by nut 57.

against the inside wall of the end of block 51. A nut 58 on the bolt 56 outside the block holds the parts together securely and rigidly at this point. By this means, the arms 50 may be collapsed downwardly to free the garment and automatically raised to normal positions by the springs when the garment is freed therefrom.

The head block 51, which thus provides room within its outer confines for the operating mechanism of the arms so that a smooth exterior may be presented to the garments and the latter be not interfered with thereby in the use of the device, is preferably in the form of an inverted cup with slightly sloping sides and a somewhat rounded bottom or upper end through which the bolt 56 passes. This cup or neck-block 51 may be of suitable sheet metal spun or pressed into the desired form, or of other suitable material or otherwise formed. It thus provides room inside for the springs and arm mechanism, and a closed outwardly smooth cover therefor, which as seen in Fig. 7 may be circular in cross section.

The arms 50 are preferably mounted at their inner ends on a pin or shaft 60 extending diametrically across the open lower end of the cup or head block 51 and having rotatable sleeve members 61 end to end on said shaft 60 inside the said end of the head block and extending substantially thereacross. The shaft or pin 60 may be riveted at its outer ends as indicated or otherwise secured in the block. The arms 50 may have at their inner ends flattened portions and lateral wings 62 which are soldered, welded or brazed to the under sides respectively of the sleeves 61, so that the latter become rigid parts of the wings and form the parts of the arms rotating on the shaft 60. They thus provide strong long sleeve bearings for the arms and keep them in proper operating positions. Any other suitable construction may be employed but this is a practical and economical method.

The arms 50 may be of any suitable material or form but in this instance are indicated as of smooth sheet metal slightly curved in cross section as shown, which provides a suitable outward contour for the garment to rest on, permits it readily to be applied thereto or to be drawn off the same, and gives longitudinal strength to the arms. In their normal positions the arms 50 engage the lower edge of the hollow block 51 which acts as a stop to hold the arms extended in the desired positions against the upward pull of the springs 52.

The springs 52 are tensioned to hold the arms in outward position for all normal use of the device but to permit them to be drawn down and collapsed to free the buttoned garment without harm thereto by a slight pull on the garment, after which the springs return the arms to normal position ready for the next garment. The garment may be revolved for inspection through the swiveled connection 25.

In operation, with the post of either form conveniently at hand and of a height and location suitable for the operator, the ironed and unbuttoned garments are opened and readily hung on the hanger in the natural manner. If they have been hung on the T-head rack or bracket 24 previously they may be conveniently taken therefrom to hang on the hanger of the post. The collar button and other buttons may then be buttoned, the collar of the garment fitting more or less loosely about the neck-block. The garment then may be revolved due to the swivel connection and inspected at the back as well as

front. When through with this, a slight pull on the garment collapses the hanger and frees the garment as described. The neck-block is small enough to pass through the buttoned collar at this time and the garment is received in perfect condition for folding, the next step in the operation.

The neck-block 19 of Figs. 1 to 5 may, if desired, be formed of the same outward shape as the block 51 of Figs. 6 and 7, and the lateral hole 30 be closed at the outer end by a suitable plug to present a smooth, even outer surface of the block at this point.

Figs. 8 and 9 show an improved swivel which is the same generally as that heretofore described, involves the same elements and may be connected to the support and to the head block in the same way, with this difference, that the threaded coupling sleeve 70, corresponding to the sleeve 25 in the other views, is provided with a depending lip 71, which may be formed by beveling off in any desired way the lower end face of the sleeve 70, as indicated at 72, Fig. 8. The nut 73, corresponding to nuts 32 and 58 in the other forms, is preferably square or four-sided, and the bolt 74 is shorter so as to bring the nut 73 up closer to the end of the swivel sleeve. As indicated, the nut is far enough below the swivel 70 to permit the hanger to swivel freely when hanging down in the normal position, but when the hanger is tipped slightly, as indicated by the dotted-line position, the side of the nut engages the lip 71 on the swivel and the hanger is prevented from turning.

A set screw 75 in the sleeve 70 enables the sleeve to be positioned with the lip 71 to the front, that is, facing the operator, and the nut 73 is correspondingly located with its lip-engaging side parallel with the hanger arms.

This construction enables the operator to 40 range the garment more satisfactorily and quickly on the hanger for buttoning. In so positioning the garment the operator is apt naturally to pull more or less on one side and then on the other of the garment, and if the hanger 45 swivels at this time the operation may be prolonged. But with this construction the slight natural pull on the sides of the garment toward the operator in putting it on the hanger tips the hanger forwardly so that the nut engages the lip 50 and the hanger is prevented from rotating and the garment may be variously shifted thereon into the desired position without loss of time or annoyance. Then when the garment and hanger 55 are released and hang down naturally, the same may be rotated freely for the buttoning and inspection of the garment.

Further description of the operation of the buttoning post is deemed unnecessary in view of what has been said. While the buttoning of garments has been done in a more or less incomplete way in laundries and inspections incidentally made, by the use of this invention the buttoning becomes a distinct step in the operation and can be completely done and inspection of the 60 garments thoroughly made.

Having thus disclosed the invention, what is claimed and desired to be secured by Letters Patent is:

1. A garment buttoning post for use in laundering garments comprising an overhead support, a hanger swivelingly supported thereon for suspending a garment in convenient buttoning position and revoluble for inspection of the garment while so suspended, said hanger including a bell-shaped neck block, side arms extending laterally

from the lower part thereof, said block having a groove in the bottom thereof, and a coiled spring secured in said groove with its projecting ends secured to the inner ends of said arms respectively and forming spring rotative connections of said arms with said block, said spring being tensioned normally to hold the arms outwardly in garment supporting position for buttoning and inspecting same and yieldable to a slight downward pull on the garment to release the same, whereby the garment may be pulled off the hanger without damage to the collar or other buttons or to the garment and when the garment is so removed the arms automatically return to normal position.

2. A garment buttoning post comprising a support, a hanger including a neck block secured to the support, side arms hinged to said neck block, said neck block being in the form of an inverted cup, side arms hinged in the lower open end of the cup, coil springs within the cup secured to said arms and to the upper part of the cup to tend to raise the same, the lower rim of the cup forming a stop for the arms to hold them normally outward in garment receiving position, said arms swinging downwardly against the tension of the springs by a pull on the garment to free the same therefrom and being returned to normal by the springs.

3. A garment buttoning post comprising an overhead support, a hanger having arms for supporting a garment, a normally free swiveling connection between said hanger and support, and means operated by tipping the hanger axially in one direction on the said support for preventing the swiveling when the hanger is so tipped.

4. A garment buttoning post comprising an overhead support, a hanger having arms for supporting a garment, a swiveled connection between the hanger and support permitting the free swiveling of the hanger when in normal suspending position, and a lock for the swivel to prevent rotation of the hanger operated by and when the hanger is tipped forwardly out of normal position.

5. A garment buttoning post comprising an overhead support, a hanger having arms for supporting a garment, a swiveling connection between the hanger and support to suspend and support the hanger from the support and permit the free rotation of the hanger when suspended normally, and locking projections on the connection and hanger brought into engagement by tipping the hanger forwardly to prevent rotation of the hanger when so tipped.

6. A garment buttoning post comprising an overhead support, a hanger having arms for supporting a garment, a swivel supporting and suspending connection between the support and hanger including a coupling sleeve attached to the support, a headed pin swiveled in the sleeve and secured to the hanger, a projection on the lower end of the sleeve, and a nut on the pin and secured to the hanger, said projection and nut being out of engagement when the hanger is suspended normally but brought into engagement when the hanger is tipped toward the projection.

whereby the hanger may be freely rotated when in normal position and may be locked against rotation when tipped toward the said projection.

7. In a device of the class described, a substantially rigid neck block about which the neck or collar portion of a garment is supported for buttoning, a pair of arms adapted to be resiliently held in extended position from the sides of said rigid neck block to hold the shoulders of the garment extended from the collar portion, spring means at the bottom of said neck block connecting to the inner ends of said arms, and mounting means for said spring means providing for pivotal mountings for said arms within the crosswise dimension of said neck block whereby a slight downward pull on the supported garment will collapse said arms downwardly to permit the buttoned collar portion of the garment to drop free of its support about said neck block.
8. In a device of the class described, a substantially rigid neck block about which the neck or collar portion of a garment is supported for buttoning, a pair of arms adapted to be resiliently held in extended position from the sides of said rigid neck block to hold the shoulders of the garment extended from the collar portion, a coil spring lying across the bottom of said rigid neck block, and means for connecting the ends of said arms to said spring to provide for a resilient downward collapse of said arms when a slight downward pull is placed on the supported garment whereby the collar portion of the garment may drop free of said neck block.
